(57) **CLAIM**

The ornamental design for a fluid emitting device, as shown and described.

DESCRIPTION

FIG. 1 is a front, left side, top perspective view of a fluid emitting device showing our new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof;
FIG. 8 is a reference perspective view thereof, showing a state in which a cover is attached to this article;
FIG. 9 is a reference view thereof, showing a state in which this article is placed on a stand; and,
FIG. 10 is a reference view thereof, showing a state in which this article with a cover attached is placed on a stand.
The broken line showing of a fluid emitting device is included for the purpose of illustrating portions of the article and forms no part of the claimed design. The broken line showing of a cover and stand is included for the purpose of illustrating environmental structure and forms no part of the claimed design.
